UNITED STATES PATENT OFFICE.

WILLIAM S. HADAWAY, JR., OF EAST ORANGE, NEW JERSEY, AND EDWARD E. ROSE,
OF SWISSVALE, PENNSYLVANIA, ASSIGNEES TO WESTINGHOUSE ELECTRIC AND
MANUFACTURING COMPANY, A CORPORATION OF PENNSYLVANIA.

ELECTRICALLY-HEATED BOILER.

1,158,486.

Specification of Letters Patent.

Patented Nov. 2, 1915.

Application filed February 11, 1910. Serial No. 543,399.

To all whom it may concern:

Be it known that we, WILLIAM S. HADAWAY, Jr., and EDWARD E. ROSE, citizens of the United States, and residents, respectively, of East Orange, in the county of Essex and State of New Jersey, and of Swissvale, in the county of Allegheny and State of Pennsylvania, have invented a new and useful Improvement in Electrically-Heated Boilers, of which the following is a specification.

Our invention relates to steam generators and it has special reference to such generators as are supplied with electrical energy and are adapted for heating purposes.

The object of our invention is to provide a simple and durable boiler which shall be capable of carrying relatively high working pressures and shall efficiently convert electrical energy into useful heat and also be adapted for connection to relatively high-voltage circuits.

Electric locomotives which are employed for drawing passenger trains of the type designed and constructed to be hauled by steam locomotives, are preferably provided with steam heating boilers in order that the cars may be maintained at a comfortable temperature in cold weather.

It is our aim to provide a boiler which shall be especially adapted for the purpose indicated above and which shall consume electric energy. We accordingly provide a boiler in which a plurality of electric heating units are substituted for the usual fire tubes, the structure of the units being such that a very large percentage of the heat generated in the resistance is transferred by conduction to the water in the boiler. In order that the boiler may be kept continuously in service, the circuit connections between the resistance units and the structure of each unit are such that one or more units may easily be cut out of circuit without materially affecting the operation of the device or increasing the electrical strains upon the units remaining in service.

Figure 1 is an end or top view and Fig. 2 is a sectional elevation of a boiler that embodies our invention. Fig. 3 is a longitudinal section, on a larger scale, of one of the heater units which are shown in Fig. 2. Figs. 4 to 9, inclusive, are detail views of the structure shown in Fig. 3.

The boiler shown in Figs. 1 and 2 comprises a cylindrical tank 6 having a head 7 at one end, heads 8 and 9 at the other end, and a plurality of heater units 10 which extend through the heads and are calked in the usual manner. Each of the heater units 60 comprises two short lengths 11 of boiler tubing connected by one or more flattened metal tubes 12 which constitute covers for the resistance element of the heater.

The heater unit may be of any suitable type, although we prefer to employ that shown and described in our co-pending application, Serial No. 777,063, filed July 2, 1913, and assigned to the Westinghouse Electric & Manufacturing Company, which is a division of the present application.

The unflattened ends 1 of the flattened tubes 12, are sealed into small heads of plugs 2 that are sealed within the inner ends of the short tubes 11, as shown in Fig. 3. The 75 insulating envelops 14 are longer than the flattened tubes and a number of mica washers 15 are fitted upon their ends within the tubes 11. The two resistance ribbons of each heater unit are joined together at their ends 80 so that current may traverse them in parallel, but the heater units themselves may be connected in any suitable manner, according to the voltage of the circuit from which electrical energy is taken.

The means for connecting the ribbons of each unit together is shown in Figs. 3, 4, 5 and 6 and comprises a short tube 3, a block 4 fitted between the ribbons within the tube 3 and two segmental blocks 5 fitted between the block 4 and the tube 3 and serving to wedge the ribbons rigidly between the said blocks. A binding screw 16 and binding plates 17 are provided to coöperate with the block 4 in electrically connecting a 95 circuit conductor (not shown) to the ribbons 13. The members 12 pertaining to each unit may be retained in proper relation to each other by means of clips 18 and screws 19, the number and location of these devices 100 being determined by the lengths of the members 12 and the particular service in connection with which they are used.

The design of the boiler is such that the length of each resistance unit is considerable and the structure of each unit is such that its resistance is comparatively high, and, consequently, the units may be con-

nected in multiple circuit even if the boiler is supplied with energy from a relatively high-voltage circuit. When connected in this manner, it is, of course, possible to exclude one or more of the resistance units in case of injury or short-circuit, or, for any other reason. The great advantage in this arrangement is that the boiler is not rendered unfit for service for any length of time simply by the failure of one of the resistance elements.

The short tubes at the ends of the heater units are used in order that the element may be expanded into the boiler heads and also form a protecting casing for the terminals of the resistance element. Insulating tubes are fitted into them for the purpose of providing an insulating lining.

It will be observed that the structure of the device is such that relatively high working pressures may be used without danger of injuring the apparatus. The steam pressure, in fact, tends to hold the walls of the flattened metal tubes very closely in engagement with the insulated resistance units so that the heat generated is more readily transferred to the water.

It is evident that the structure illustrated may be utilized for various purposes and that structural modifications may be effected within the spirit and scope of our invention.

We claim as our invention:

1. An electrically heated boiler comprising a fluid-containing vessel and a heating element consisting of a plurality of resistance units, the ends of which are received in a single pair of oppositely disposed terminal devices.

2. An electrically heated boiler comprising a fluid-containing vessel and a heating element consisting of a plurality of flattened tubular units, the ends of which are received in a single pair of terminal devices.

3. An electrically heated boiler comprising a fluid-containing tank and a plurality of heating units extending through the tanks and severally comprising insulated resistance elements, metal sheaths or casings for said resistance elements and short metal tubes in which said sheaths or casings are sealed.

4. An electrically heated boiler comprising

ing a fluid-containing tank and a plurality of heating units extending through the tank from end to end and comprising relatively short end tubes which are headed into the ends of the tank, interposed flattened metal tubes that are sealed into the short tubes, and insulated resistance units disposed within the flattened tubes.

5. An electrically heated boiler comprising a fluid-containing tank and a plurality of heating units extending through the tank from end to end and comprising relatively short end tubes headed into the ends of the tank and provided with insulating linings, interposed flattened metal tubes sealed into the short tubes, and resistance units disposed within the flattened tubes and separated therefrom by heat-resisting insulation.

6. An electrically heated boiler comprising a fluid-containing tank and a plurality of heating units extending through the tank from end to end and comprising relatively short end tubes headed into the ends of the tank and provided with insulating linings, interposed flattened metal tubes sealed into the short tubes, and resistance ribbons located within the flattened tubes and separated therefrom by insulation partially composed of clear mica.

7. An electrically heated boiler comprising a fluid-containing tank and a plurality of heating units extending through the tank from end to end and comprising relatively short end tubes headed into the ends of the tank and provided with insulating linings, interposed flattened metal tubes, sealed into the short tubes and resistance ribbons having a plurality of slots cut alternately in opposite edges to provide a zigzag path for electric current, said ribbons being located within the flattened tubes and separated therefrom by insulation composed of an inner layer of clear mica and an outer layer of covering of molded mica insulation.

In testimony whereof, we have hereunto subscribed our names this 5th day of Feb. 1910.

WILLIAM S. HADAWAY, JR.
EDWARD E. ROSE.
